UNITED STATES PATENT OFFICE.

LEWIS HERRICK, OF NEW HAVEN, CONNECTICUT.

DRILLING-MACHINE.

SPECIFICATION forming part of Letters Patent No. 293,246, dated February 12, 1884.

Application filed May 11, 1883. (No model.)

To all whom it may concern:

Be it known that I, LEWIS HERRICK, a citizen of the United States of America, residing at New Haven, in the county of New Haven 5 and State of Connecticut, have invented certain new and useful Improvements in Drill-Presses, of which the following is a specification, reference being had therein to the accompanying drawings.

10 My invention relates to improvements in that class of drill-presses in which both manual and pedal power may be used to elevate the work-supporting table.

15 The object of my invention is to provide means for steadyng and assisting the motion of the foot in elevating the work-supporting table of a drill-press.

20 My invention consists in the hereinafter-described means for attaining said objects.

25 In the drawings, Figure 1 represents a side elevation of my improvement; Fig. 2, a sectional view (looking downward) on line $x-x$ of Fig. 1; Fig. 3, a detail view of the curved lever, and Fig. 4 a detail view of the pedal-lever.

Similar letters of reference indicate corresponding parts throughout the different views.

30 A is the base of the press, from which rises the vertical post B, and to the top of the latter the frame C is secured. Said frame C bears the driving mechanism D of the drill-stock E. About midway of said post B, and directly beneath drill-stock E, is the frame F. Said frame is secured to the post (so as to be 35 vertically adjustable) by means of bolts f, and is provided with vertical guideways, in which slides the sectional rod G. Upon the upper extremity of said rod is fixed the work-supporting table H. Said rod is divided into 40 two sections, whose ends overlap and are held together by collars g, which embrace said sections, and are provided with set-screws to enable the rod to be extended or contracted and fixed in position at a greater or less distance 45 from the drill. In order to retain said table within the desired bounds, I provide the gage I, secured at one end to said table, and provided with nuts i i' above and below said frame, whereby the play of the table is restricted within the desired bounds. By regulating these nuts it will be seen that the vertical movement of said work-bearing table is

restricted, and the danger of drilling into the body of the table avoided. The free end of the rod G is pivoted between the ears k, extending from the middle of the convexed part of the curved lever K. Said lever has one of its arms, k', of about twice the length of the other, and this long arm is provided on the outside, near its extremity, with a pin, k², for the purpose hereinafter set forth. The lever K is provided with transverse orifices at the end of the short arm and about midway of the long arm, and a pivot-pin passes through said orifices and like orifices formed in ears 55 extending upward from base A, thus pivoting said lever upon said base. Immediately above the pivotal point of the long arm said lever K is provided with an upright arm, k³, to which is bolted a hand-lever, L. In the rear of lever K a perforated lug extends upward from the base A, and to this lug is pivoted the foot-lever M. Said lever or treadle, opposite the end of the long arm k', is provided with a longitudinal slot, m, in which works the afore- 60 said pin k² of the lever K. It is furthermore provided upon its free extremity with a foot-rest, m'.

The operation of my invention is as follows: The table H is adjusted to any desired height 80 by means of the bolts f and the rod G. The article to be operated upon is then placed upon the table and the drill set in motion. The nuts i i' are then adjusted to regulate the depth of the cut. As the drill cuts, the table is ele- 85 vated by pressing the foot upon the pedal M and pressing backward the lever L, whereby the curved portion of the lever K is elevated and the rod G and table H raised.

In cases where the table is stationary and the drill-stock spindle moves up and down, it is obvious that the rod G may be disconnected from the table and connected with the spindle, so as to actuate the latter.

Having thus described my invention, what I 95 claim is—

1. In a drill-press, the curved lever K, connected at the middle of its curvature with the table-bearing rod, fulcrumed as described, and provided with a long arm, k', and an upright arm, k³, said long arm connected with a treadle, and said upright arm adapted to carry a hand-lever, substantially as and for the purposes described.

2. The combination, with the curved lever K, having a long arm, k' , provided with a pin, k^2 , of the pedal-lever M, pivoted in rear of said curved lever, and provided with a longitudinal slot, m, adapted to fit over the afore-
5 said pin, as and for the purposes described.

3. The combination, with the work-table and the elevating mechanism, of the rod G, composed of two sections held together by collars

and set-screws, and the screw I, provided with 10 nuts, as described, whereby said table may be adjusted, for the purposes set forth.

In testimony whereof I affix my signature in presence of two witnesses.

LEWIS HERRICK.

Witnesses:
